Dec. 1193

Birdsill Holly, of Lockport, N. Y.
Letters Patent No. 1193. Dated Jan'y 24. 1860.

The schedule referred to in these Letters Patent and making part of the same.

To all whom it may concern:

Be it known that J. Birdsill Holly, of Lockport, in the County of Niagara, and state of New York, have invented or produced a new design for a Cistern Pump, and I do hereby declare that the following is a full and exact description of the same, reference being had to the accompanying drawing, which is a perspective view thereof.

As represented in the drawing my improved form or configuration consists of a skeleton base of rectangular form, with four supporting members *a. a.* at the corners, diminishing diametrically, and uniting in an ogee arch near their junction with the cylinder *b.*

This cylinder is about half the diameter only of the base and top, in order to produce symmetry of proportion, and I prefer to make it of brass or other polished metal, to preserve an effective contrast between that and the other parts, which are japanned or painted.

At the lower extremity of the cylinder is a flange *c.* of bold projection with a series of small and uniform pendants *c. c.* dropping from its periphery like drapery, and agreeably covering the line of union between the cylinder and base.

Above the cylinder the pitcher top arises in octagon form, gradually expanding to the terminating flange at the top. One of the planes of the octagon is lost in the bold open sprout *d.* while the remaining ones give agreeable relief to the eye, and a form both seemly in itself, and harmonious with the base.

The combination of the octagonal, cylindrical and rectangular sections produces a novel and agreeable style of ornamental exterior, while the planes *e. e.* of the octagon portion afford a convenient surface for attaching the seat of the pedestal for the lever *g.* which is removable and may be changed to either one as may best suit the requirements of its situation.

I claim the design or configuration described and shown, consisting

Excluding of the rectangular open base, cylindrical central division *b.* and open octagon top.

J. M. P. *Fraser.*

J. S. Hopkins. *3*

Birdsill Holly.
